UNITED STATES PATENT OFFICE.

CARROLL KNOWLES, OF HARTFORD, CONNECTICUT, ASSIGNOR TO PRATT & WHITNEY COMPANY, OF NEW YORK, N. Y., A CORPORATION OF NEW JERSEY.

HOB-GRINDING MACHINE.

Application filed April 9, 1924. Serial No. 705,250.

My invention relates to grinding machines and particularly to machines for grinding hobs.

One object of my invention is to provide a hob grinding machine that shall be automatic in operation and that shall grind the sides of the hob teeth to involute helicoids.

Another object of my invention is to provide a hob grinding machine of the above indicated character that shall control the starting and the stopping of the relieving movements of a grinding wheel slide in accordance with the movement of a blank carrying carriage.

Another object of my invention is to provide a hob grinding machine having a rotating hob mounted on a carriage and a grinding wheel mounted on a transversely movable slide, that shall stop the relieving movements of the slide and withdraw the wheel from engagement with the blank when the blank carrying carriage is at one end of its movement, and that shall start the relieving movements of the slide and move the wheel into engagement with the blank when the blank carrying carriage is at the other end of its movement.

A further object of my invention is to provide a hob grinding machine that shall form involute helicoids on the sides of the hob teeth, that shall have improved means for rotating the hob while moving the blank carrying carriage, and that shall have improved means for feeding the wheel slide and for controlling the relieving movements.

In the art of grinding, it is well known that it is difficult to grind a continuous screw thread with any degree of accuracy unless the lead of the thread is very small. However, it is a relatively simple matter to grind a surface which is in the form of an involute helicoid. The properties of involute helicoids are discussed at some length in the patent to Ernest Wildhaber, No. 1,571,359 granted February 2, 1926, and in the patent to Earle Buckingham, No. 1,540,757 granted June 9, 1925. In view of the complete disclosure in the above patents an extended description of the involute helicoid will not be given in this application.

An involute helicoid may be considered as the surface formed by continuously advancing a line along a helix while maintaining

the line tangent to the helix. Inasmuch as the involute helicoid is formed by lines tangent to a helix, it is apparent a grinding plane may be provided which includes any line which is tangent to the helix. Therefore, it is apparent that the grinding of an involute helicoid is a relatively simple matter. However, it is impossible to accurately grind a continuous screw thread with any degree of accuracy unless the lead of the thread is relatively small. The reason for the difficulty in grinding a screw surface is the inability of the grinding wheel to cut along the exact line by which the thread was initially formed.

In a machine constructed in accordance with my invention, a rotating blank is mounted on a carriage and a grinding wheel is mounted on a slide which is movable transversely with respect to the blank. A set of gearing, which is carried by the carriage, is operated from the main frame of the grinding machine and serves not only to rotate the blank but also to effect longitudinal movement of the carriage. The gearing carried by the carriage is continuous and effects, as heretofore set forth, not only the rotation of the blank but also operates a feed screw which is carried by the blank supporting carriage. The feed screw engages a nut which is secured to the main frame of the machine.

The wheel slide is subjected to a resilient force tending to move it away from the blank and is operated by means of a cam member to effect relieving movements. An adjustable slide, which carries a projecting lug, serves to connect the relieving cam member to the relieving slide. At one end of the movement of the carriage, the adjustable slide is so operated as to disconnect the relieving cam from the relieving slide and accordingly to prevent any relieving movements. At such time, the relieving slide is moved away from the blank by the resilient means above mentioned. At the other end of the carriage movement, the adjustable slide is so moved as to connect the relieving cam to the relieving slide and to start the relieving movements. At such time, the grinding wheel is returned into engagement with the blank.

The movement of the blank carrying car-

riage is automatic in its operation. The carriage moves in one direction in accordance with the lead of the thread on the hob blank and in accordance with the rotation of the blank. In the opposite direction, the carriage is moved at a relatively rapid rate inasmuch as the grinding wheel is not in engagement with the blank. When the carriage is at one end of its movement, a feeding movement by the wheel slide is automatically effected.

In the accompanying drawings:

Figure 1 is a front elevational view of a machine constructed in accordance with my invention.

Fig. 2 is a plan view of the machine shown in Fig. 1.

Fig. 3 is a sectional view along the line 3-3 of Fig. 2.

Fig. 4 is a sectional view along the line 4-4 of Fig. 2.

Fig. 5 is a partial end view of the machine showing the gearing connected to the headstock spindle.

Fig. 6 is an end view of the machine from the right of Fig. 1 and shows certain parts in section.

Fig. 7 is a view of the cam mechanism for controlling the relieving slide and the carriage.

Fig. 8 is an end view of the mechanism shown in Fig. 7.

Fig. 9 is a sectional view along the line 9-9 of Fig. 7.

Fig. 10 is a detail view of the means for accentuating the positions of the cam drum.

Fig. 11 is a view from the rear of the machine.

Fig. 12 is a sectional view through the cam slide along the line 12-12 of Fig. 3.

Fig. 13 is a plan view, partially in section, of one mechanism for adjusting the slides.

Fig. 14 is a sectional view along the line 14-14 of Fig. 13.

Fig. 15 is a plan view of the wheel dressing plate.

Referring to the drawings, a machine is illustrated comprising a main frame 1, having a blank carrying carriage 2 mounted thereon. The carriage 2 is fitted to suitable ways 3 and 4 which are formed on the main frame 1. The carriage 2 is provided with a headstock 5 and a tailstock 6. The headstock 5 is secured to the carriage and the tailstock 6 is adjustable along the carriage. Preferably suitable bolts 7 are provided for holding the tailstock 6 in position on the ways which are formed on the carriage. A lever 8, which is spring retracted, is provided for longitudinally moving the tailstock center 9 to mount a blank in position.

The carriage 2 is moved by power supplied to a pulley 10. The pulley 10 is rotatably mounted on a shaft 11 which has bearings 12 and a bearing in the bracket 12a. A

friction clutch 13 of any suitable type is provided for connecting the pulley 10 to the shaft 11. The friction clutch is controlled by a hand lever 14 which is mounted on a rod 15. The rod 15 carries a lever 16 having arms which are fitted to a groove 17 formed in the friction clutch 13. The shaft 11 carries a bevel gear wheel 18, which meshes with a bevel gear wheel 19, for operating a cam mechanism 20 shown in Figs. 7, 75 and 9 of the drawings.

The cam mechanism 20 serves to control not only the movements of the carriage 2 but also to control the movements of a relieving slide 21. A suitable box 22 is attached to the main frame 1 for supporting the mechanism 20. The bevel gear wheel 19, which meshes with the bevel gear wheel 18 on the shaft 11, is carried by a shaft 23. A pinion 24 is mounted on the end of shaft 23 adjacent to the bevel gear wheel 19. The pinion 24 is keyed to the shaft 23 for a purpose to be hereinafter set forth. A two-way friction clutch 25, which is mounted on the shaft 23, is provided for transmitting power from the shaft 11 to a shaft 26. The clutch 25 carries two gear wheels 27 and 28. The gear wheel 27 meshes directly with a gear wheel 29 on the shaft 26 and the gear wheel 28 is connected to a gear wheel 30 on the shaft 26 through an idler gear wheel 31. According to the position of the clutch 25, either the gear wheel 28 or the gear wheel 27 is directly connected to the shaft 23 and the bevel gear wheel 19. Accordingly, the position of the clutch 25 determines the direction of rotation of the shaft 26. The position of the friction clutch 25 is automatically controlled by a cam drum 32.

The cam drum 32 is mounted on a shaft 105 33 and is operated under the control of a two-way jaw clutch 34. The jaw clutch 34 is mounted on a shaft 35 and comprises two end members 36 and 37 and a central member 38. The end members 36 and 37 are rotatably mounted on the shaft 35 and the central member 38 is splined to the shaft 35. The end member 36 carries a gear wheel 39 which meshes with an idler gear wheel 39a. The gear wheel 39a meshes with a gear wheel 40 which is attached to the cam drum 32. The end member 37 carries a gear wheel 41 which meshes with a gear wheel 42 attached to the cam drum 32. A gear wheel 43, which is keyed to the shaft 35, meshes directly with the gear wheel 24 which is mounted on the shaft 23. Thus, when the teeth on the central member 38 of the jaw clutch engage the teeth on the end member 36, the cam drum 32 is rotated in one direction, and when the teeth on the opposite end of the central member 38 engage the teeth on the end member 37, the cam drum 32 is rotated in a reverse direction. It will be noted the bevel gear wheel 19 and the 130

gear wheel 24 on the shaft 23 are always in rotation when the friction clutch 13 is in an operative position.

The cam drum 32 automatically controls 5 the two-way clutch 25 and the jaw clutch 34. A lever 44, which is pivotally supported in the box 22, as shown in Fig. 9 of the drawings, carries a roller 45. The roller 45 is fitted to a cam groove 46 on the cam drum 32. The lever 44 has a bifurcated end portion which is fitted to a groove 46a in the two-way clutch 25. Thus, the position of 10 the two-way clutch 25 and accordingly the direction of rotation of the shaft 26 is controlled by the cam groove 46 on the cam drum 32.

A cam groove 48 is formed in the drum 32 for controlling the movement of the jaw clutch 34. A lever 49, which is mounted on 20 a shaft 50, carries a roller 51. The roller 51 is fitted to the groove 48. The opposite end of the lever 49 is fitted to a groove 52 in the central member 38 of the jaw clutch 30. The shaft 50 not only carries the lever 25 49 but also has a lever 53 secured to it. The lever 53 is connected to a reversing rod 54. The reversing rod 54 is controlled, in a manner to be hereinafter set forth, in accordance with the movement of the carriage 30 2. When the carriage 2 is at either end of its travel, the reversing rod 54 is operated for moving the central member 38 of the jaw clutch 34.

Referring to Fig. 7 of the drawings, it 35 will be noted the cam groove 48 is so formed in the drum 32 as to insure the movement of the drum in a direction the reverse of the last movement. The roller 51 on the lever 49 is shown in engagement with a shoulder 55 on the side of the cam groove. Accordingly, the reversing rod 54 can only be moved in a direction to effect engagement between the central member 38 of the jaw clutch and the end member 36. Such movement with 40 the jaw clutch will effect rotation of the drum 32 in a counter-clockwise direction, as shown in Fig. 9 of the drawings. The movement of the drum 32 is continued until the roller 51 engages a shoulder 56 on the side 45 of the cam groove. In such position of the drum 32, the central member 38 of the jaw clutch is moved away from the end member 36 to prevent any further movement thereof. In the last mentioned position of the drum, 50 it will be noted the reversing lever 54 can only be operated in a direction to effect engagement between the central member 38 and the end member 37. When the jaw clutch is so operated, it will be noted the 55 cam drum 32 is operated in a clockwise direction as shown in Fig. 9 of the drawings. As heretofore set forth, the direction of rotation of the cam drum 32 controls the direction of rotation of the shaft 26. However, 60 the rotation of the shaft 26 is not stopped

by the stopping of the rotation of the cam drum 32.

A third cam groove 58 is formed in the cam drum 32 for controlling the relieving movements of the slide 21. A lever 59, 70 which is mounted on a shaft 61, carries a roller 60. The roller 60 is fitted to the cam groove 58. The shaft 61, which has a bearing in the main frame 1, carries a second lever 62, as shown in Fig. 3 of the drawings. 75 The lever 62 is connected by a link 63 to a cam slide 64. The cam slide 64 is adapted to have vertical movement in the relieving slide 21 and serves to control the relieving movements as hereinafter set forth. A 80 spring member 65, which is secured to the end of the lever 62 exerts a force normally tending to hold the slide 64 in a raised position. It may be noted that in the raised position of the cam slide 64, relieving movements are effected by the slide 21 and a grinding wheel 66 is moved into engagement with a blank 67.

Referring again to Figs. 7, 8 and 9 of the drawings, the shaft 26, which is controlled by the cam mechanism 20, carries a worm member 68. The worm member 68 meshes with a worm wheel 69 which is mounted on a cam shaft 70. The cam shaft 70 carries a cam member 71 which is adapted 90 to cooperate with a lug 72. The lug 72 projects from the cam slide 64, as shown in Fig. 3 of the drawings.

A lever 73, which is pivotally supported 100 on the main frame 1 of the machine as shown in Fig. 3, is connected near the upper end thereof to the slide 125. The lower end of the lever 73 is connected to a spring 74. The spring 74 is held and adjusted by a knob 75 which projects from the front of the machine. Thus, it is apparent the spring member 74 exerts a force through the lever 73 105 tending to move the relieving slide 21 away from the blank carrying carriage.

Assuming the cam slide 64 to be in the position shown in Fig. 3 of the drawings, the rotation of the cam member 71 in a clockwise direction will effect relieving movements by the slide 21. Inasmuch as the cam member 71 can only operate the relieving slide 21 when the lug 72 is in the raised position shown in Fig. 3, it is apparent when the slide 64 is lowered the relieving movements are automatically stopped. Not only are the relieving movements stopped, when the slide 64 is lowered, but the grinding wheel is moved away from the blank. At the end of the grinding movement by the carriage 2, the cam drum 32 through the rod 61 and levers 59 and 62 lowers the cam slide 64 to stop the relieving movements and moreover to withdraw the grinding wheel from engagement with the blank. At the end of the return stroke by the carriage, the cam slide 64 is raised not only to move the 110 115 120 125

grinding wheel into engagement with the blank but also to start the relieving movements.

The shaft 26, which carries the worm member 68 for operating the relieving slide, also carries a worm member 77 for not only rotating a blank carrying spindle 78 but also for operating the blank carrying carriage 2. The worm member 77 meshes with a worm wheel 79. The worm wheel 79 is splined to and slidably mounted on a sleeve member 80. The sleeve member 80 is rotatably mounted on a carriage lead screw 81, as best shown in Figs. 1, 4, 5 and 6 of the drawings.

The sleeve member 80 carries a gear wheel 82 which meshes with a gear wheel 83. The gear wheel 83 is supported on a slotted arm 85 by a stud bolt 84. The arm 85 is secured to a lug 86 which projects from the carriage 2, as shown in Fig. 3 of the drawings. The arm 85 is secured to the lug 86 by means of two bolts 87 and 88 which project through a slot 89 in the arm as best shown in Figs. 3 and 5 of the drawings. The gear wheel 83 meshes with a gear wheel 89 which is mounted on a shaft 90. The shaft 90 is provided with suitable bearings in the headstock of the machine and carries a gear wheel 91 which meshes with a gear wheel 92 on the spindle 78. The gear wheel 92 meshes with a gear wheel 93 which is mounted on a shaft 94. The shaft 94 is provided with suitable bearings in the headstock and carries a second gear wheel 95. The gear wheel 95 meshes with a gear wheel 96 which is carried by a stud bolt 97. The stud bolt 97, which also carries a gear wheel 98, is mounted on the slotted arm 99. The arm 99 is pivotally supported by a bolt 100 and is held in position by a bolt 101. The stud bolt 97 projects through a slot 102 formed in the arm and the bolt 101 projects through an arcuated slot 103 which is formed in the arm. The gear wheel 98 meshes with a gear wheel 104 which is secured to the lead screw 81. Thus, it is apparent the train of gearing, which serves to rotate not only the blank carrying spindle 78 but also the lead screw 81, is continuous. Moreover, it is apparent the rotation of the blank and also the movement of the carriage 2 must be in timed relation to the relieving movements by the grinding wheel inasmuch as the shaft 26 directly controls each of such movements.

The machine is shown in position for grinding hobs having right-handed threads. In case it is desired to grind hobs having left-handed threads, it is necessary to reverse the direction of rotation of the screw 81. In order to reverse the direction of rotation of the screw 81, an idler gear wheel 105 is interposed between the gear wheel 95 and the gear wheel 96. In Fig. 4 of the drawings, the gear wheel 105 is shown supported on an arm 106 by means of a stud bolt

107. The arm 106 is supported on the headstock of the machine. When it is desired to use the gear wheel 105 for reversing the direction of rotation of the lead screw 81, its position on the arm 106 is reversed in order to be in line with the gear wheels 95 and 96.

The lead screw 81 is provided with suitable bearings on the carriage 2 and threadably engages a nut 108 which is secured to the main frame of the machine. The nut 108 comprises a worm wheel 109 having a hub portion 110 attached thereto and a threaded sleeve 111 which is preferably cast to the hub 110. The threaded sleeve 111 engages the threads on the lead screw 81. The nut 108 is supported in a bracket 112 as shown in Figs. 4 and 6 of the drawings. The bracket 112 is secured to a web 113 of the main frame 1 by means of three bolts 114. A lever 115 is threadably connected to an end portion of the bracket 112 as shown in Fig. 4. The lever 115 is adapted to engage a washer 116 which is in engagement with a nut 117 on the end of the hub 110. By so rotating the lever 115 as to wedge it against the washer 116, it is apparent the nut 108 is secured to the web 113, and thus is prevented from rotating with the lead screw 81.

The lever 115 is connected to a rod 118 which extends through the main frame to an operating knob 119 on the front of the machine. When the knob 119 is pulled out from the machine, the lever 115 is operated to hold the nut 108 in a stationary position. Thus, rotation of the lead screw 81 effects movement of the carriage 2. However, if the knob 119 is pushed inwardly, the nut 108 is free to rotate in the bracket 112. The worm wheel 109 on the nut 108 is rotated by means of a worm member 120 on a shaft 121 for adjusting the carriage 2 with respect to the grinding wheel. The shaft 121 is rotated by means of a hand wheel 122.

A feed shaft 123, which is manually operated by a hand wheel 124, is provided for operating an adjusting slide 125 transversely with respect to the carriage 2. The shaft 123 is provided with suitable bearings in the main frame 1 and carries a pinion 126 which meshes with a gear wheel 127. The gear wheel 127 meshes with a pinion 128 which is mounted on a screw shaft 129. The screw shaft 129 is rotatably supported in the relieving slide 21 and is connected to the adjusting slide 125 by means of a nut 130. Upon referring to Fig. 3 of the drawings, it will be noted the gear wheel 127 is much wider than the pinion 128. By reason of the difference of width between the pinion and the gear wheel, the slide 21 may effect relieving movements without separating the pinion from the gear wheel.

A wheel base 131, which is mounted on the main frame 1 of the machine, serves to sup-

port the adjusting slide 125. The relieving slide 21 operates in a way 132 formed in the adjusting slide 125 as shown in Fig. 11 of the drawings and rests on straps 133. The 5 straps 133 are carried by the adjusting slide 125. A downwardly projecting portion 134 of the relieving slide 21 has a slot 135 formed therein, as shown in Fig. 12 of the drawings. The cam slide 64 is mounted in the 10 slot 135 and is held in position by means of two plates 136, as shown in Figs. 3, 11 and 12 of the drawings. The slide 21 carries a pin 137, shown in Figs. 3 and 11 of the drawings, which projects through an opening 138 15 in a bracket 139 and engages a plunger 140. The bracket 139 is secured to the wheel base 131 in any suitable manner. The plunger 140 is resiliently held in the position shown in Fig. 3 by means of a spring member 141. 20 The spring member 141 is disposed between the head of the plunger 140 and a plug which is secured to the plate 139. The pin 137 on the relieving slide 21 cooperates with the resiliently supported plunger 140 to cushion 25 the return movements of the relieving slide.

The adjusting slide 125 is mounted on ways 142 formed on the base member 131 and is held in position by suitable straps 143. The adjusting slide 125 carries a slide 144 30 which is adjustable with respect to the slide 125. The slide 144 is fitted to a guideway 145 on the adjusting slide 125. The means for adjusting the slide 144 with respect to the slide 125 is best shown in Figs. 11, 13 35 and 14 of the drawings. A small shaft 146, which projects from the side of the slide 144, carries an operating knob 147. The opposite end of the shaft 146 carries a bevel gear wheel 148 which meshes with a bevel gear wheel 149. The bevel gear wheel 149 is 40 mounted on a feed shaft 150. The feed shaft 150 is threadably connected to a nut 151 which is secured to the adjusting slide 125. Thus, it is apparent by operating the knob 45 147, the slides 144 and 145 are adjusted relative to one another for varying the transverse position of the grinding wheel with respect to the blank carried by the carriage 2. This mechanism is chiefly used for dressing 50 the wheel.

The slide 144 carries a swiveling plate 153 which in turn carries the grinding wheel 66. The plate 153 is pivoted on a bolt 154 which projects from the slide 144. The plate 55 153 is held in any adjusted position by means of a clamping bracket 155 which is shown in Fig. 3 of the drawings. The bracket 155 is clamped to the plate 153 by means of two bolts 156 which are connected to the slide 60 144. Preferably a scale 157, as shown in Fig. 2 of the drawings, is formed on the clamping bracket 155 in order to indicate the angular position of the swivelling plate 153. Two set screws 158, which project through 65 arcuated slots 159, are also adapted to secure

the swivelling plate 153 in any set position. Two upwardly projecting plates 160 and 161, which are preferably formed integral with the swivelling plate 153, are provided for supporting a vertically movable wheel slide 70 162. The wheel slide 162 is provided with a tongue 163, as shown in Fig. 2 of the drawings, which is fitted to a groove in either the plate 160 or the plate 161. The slide is secured to one of the plates by means of bolts 75 164 which project through slots 165.

The grinding wheel 66 is mounted on a spindle 167 which has a bearing in the wheel slide 162. The spindle 167 also carries a pulley 168 which is connected by a suitable belt 80 169 to a pulley 170 on a shaft 171. The shaft 171 is provided with bearings on arms 172 which project from a plate 173. A pulley 174, which is mounted on the shaft 171 between the bearings, is connected to a suitable 85 source of power.

The plate 173 is provided with two sets of notches 177 and 178, as shown in Fig. 2 of the drawings, for securing it by means of bolts 179 to the swivelling plate 153. The 90 bolts 179 project through a slot 180, which is formed in the swivelling plate 153. A bolt 181, which passes through the slot 180 formed in the swivelling plate is secured to the plate 173 and serves as a pivot when 95 positioning the pulley 170 with respect to the pulley 168. If the grinding wheel on the slide 162 is supported on the plate 161, the plate 173 is secured to the plate 153 with the notches 178 in the plate 173 aligned with the slot 180 in the swivelling plate 153. The pulley 170 is placed on the end of the shaft 171 which will align it with the pulley 168 on the end of the wheel spindle 167. If the 100 grinding wheel slide 162 is changed from the plate 161 to the plate 160 for grinding the opposite sides of the hob teeth, the position of the plate 153 is reversed and the pulley 170 is changed to the opposite end of the shaft 171. By such means, the pulley 170 is 105 easily adjusted in line with the pulley 168 when the grinding wheel is mounted on the plates 160 and 161.

A bracket 182 is secured to the slide 144 by means of bolts 183. Two hand operated bolts 184 are provided for firmly clamping the bracket 182 in any set position. The bracket 182 carries an adjusting slide 185 having an adjusting plate 186 formed integral therewith. The adjusting slide is 115 fitted to a guideway 187 formed in the bracket 182 and is held in position by two straps 188 and 189. A screw 190, which is operated by a knob 191, is supported in the slide 185. The screw 190 engages a nut 192 120 which is secured to the bracket 182. Thus, by operating the knob 191, the position of the dressing plate 186 with respect to the grinding wheel is varied.

The dressing plate 186, which is best 125 130

shown in Fig. 15 of the drawings, carries two adjusting plates 193 and 194. The two plates are pivoted about a pin 195. The plate 193 carries a pin 196 and is adjusted 5 by means of a screw 197. The plate 194 carries a pin 198 and is adjusted by means of a screw 199. The three pins 195, 196 and 198 serve as reference points for dressing a conical grinding wheel. Two blocks 200 and 201 10 serve as reference points for dressing the periphery of a grinding wheel. The members which are used for dressing the grinding wheel are completely illustrated and described in a companion application of Carl 15 Schramm Serial No. 691,398 filed February 8, 1924. One of the dressing members is shown in dot and dash lines on the plate 194. By reason of the complete description given in the Schramm application, it is deemed 20 unnecessary to further describe the dressing of the wheel in this application.

A pin 202, which projects from the top of the wheel slide 162, engages a lug 203 projecting from the bottom of the plate 186. 25 Preferably, the plate 186 is so positioned that the pin 202 on the wheel slide is in engagement with the lug 203 when the grinding wheel axis is in the same plane as the axis of the blank. It may be noted that the 30 reference plane through the axis of the wheel and the axis of the blank must be parallel to the plane of the relieving movements. When it is desired to elevate the grinding wheel with respect to the blank, the scale 35 204 and the markings on the knob 191 serve to accurately measure the position of the axis of the grinding wheel with respect to the axis of the blank.

The automatic operation of the carriage 2 40 is controlled by two dogs 205 and 206. The dogs 205 and 206 are held by bolts 207 and 208 in a slot 209 which is formed in the carriage 2. The dog 206 has a lug 210 projecting from it. The lug 210 carries an adjusting bolt 211 which serves to control the 45 amount of feed in a manner to be herein-after set forth. A lever 212, which is rotatably mounted on a sleeve on the shaft 123, is positioned in alignment with the dogs 205 and 206. At the end of the movement of the carriage 2 in one direction, the lever 212 is operated by the dog 205 and at the end of the movement of the carriage in the opposite direction, the lever 212 is operated by the 50 dog 206. The lever 212 is provided with two projecting arms 213 and 214. One of the arms 213 and 214 is connected by a rod 215 to a bell crank lever 216. The bell crank lever 216 is pivotally mounted on the 55 main frame 1 and is connected to the reversing rod 54 as best shown in Figs. 1 and 2 of the drawings. When a hob having a right-hand thread is being ground, the rod 215 is connected to the arm 214 and when a 60 hob having a left-hand thread is being

ground, it is necessary to connect the rod 215 to the arm 213. The control of the cam mechanism 20 by the reversing rod 54 was described when reference was made to Figs. 7, 8 and 9 of the drawings.

Referring to Figs. 7, 8 and 9 of the drawings, a plate 217 is secured to the hob portion of the bell crank lever 49 for accentuating the position of the reverse rod 54. The plate 217 has a notch 218 formed in it for cooperating with a spring pressed plunger 220. Referring to Figs. 7, 8, 9 and 10 of the drawings, a disk 239 is mounted on the end of the cam drum 32 for accentuating the extreme positions of such cam drum. Two notches 240 and 241 are formed in the disk 239 for cooperating with a spring pressed plunger 242. The plunger 242 is mounted in a lug 243 on the side of the box 22.

The automatic feeding of the grinding wheel 66 towards the blank 67 is controlled by a ratchet wheel 221. The ratchet wheel 221 is fixedly connected to the shaft 123 which operates the feed shaft 129. A pawl 222, which is mounted on a lever 223, is adapted to engage the teeth on the ratchet wheel. The lever 223 is rotatably mounted on a sleeve 224 which is mounted on the frame of the machine. The lever 223 is so positioned as to be engaged by the bolt 211 on the dog 206 near the end of the movement of the carriage 2 towards the left as shown in Fig. 1 of the drawings. The lever 223 is provided with an arm 225 which is positioned between two set screws 226 and 227. The set screws 226 and 227 are mounted on arms projecting from a bracket 228. The bracket 228 is secured to the main frame 1 and is provided with an arm 229 for supporting a reference pin 230. A plate 231, which is rotatably mounted on the shaft 123 adjacent to the hand wheel 124, carries a shield 232 which projects over the teeth on the ratchet wheel 221. A pin 233 projects through the plate 231 and engages the teeth on the ratchet wheel 221. The plate 231 is set in any predetermined position with reference to the reference point 230 in order to stop the feeding movements after a predetermined feeding movement. The shield 232, which is mounted on the plate 231, is moved after a predetermined feeding movement to a position for separating the pawl 222 from the ratchet wheel 221.

A counterweight 235 is connected to the carriage 2 by means of a flexible connection 236, as shown in Figs. 3 and 4 of the drawings. The counterweight maintains a constant pressure in one direction on the gearing which operates the carriage 2 and rotates the hob blank.

In a machine constructed in accordance with my invention, it will be noted the carriage 2 is automatically reciprocated in ac-

cordance with the position of the two dogs 205 and 206. The dogs 205 and 206 through the reversing lever 54 and the associated parts not only control the reciprocating movement of the carriage 2 and the blank but also start and stop the relieving movements of the grinding wheel. Moreover, it will be noted the grinding wheel is withdrawn from engagement with the blank during the movements of the carriage in one direction and is moved into engagement with the blank during the movement of the carriage in an opposite direction. The grinding wheel is so mounted that it may be accurately positioned any desired distance above or below the axis of the blank in order to form involute surfaces on the teeth of the hob being ground.

Modifications in the machine and in the arrangement and location of parts may be made within the spirit and scope of my invention and such modifications are intended to be covered by the appended claims.

What I claim is:

1. In a machine for grinding hobs, the combination with a carriage having a blank mounted thereon, a grinding wheel, a slide for supporting the grinding wheel, means for rotating the blank, means for moving the carriage in one direction in accordance with the lead of the thread on the hob and the rotation thereof, and means for automatically returning the carriage to initial position when the end of the hob thread is reached, of means for effecting feeding movements by the slide in accordance with the movement of the carriage and for effecting relieving movements of the slide in accordance with the blank rotation, means for stopping the relieving movements of the slide during the time the carriage is being returned to initial position, and means for so positioning the grinding wheel with respect to the blank as to form involute surfaces on the blank teeth.

2. In a machine for grinding hobs, the combination with a carriage having a blank mounted thereon, a grinding wheel, a slide for supporting the grinding wheel, means for effecting relieving movements by the slide in timed relation to the rotation of the blank, means for moving the carriage in accordance with the blank rotation to a predetermined point and for automatically returning the carriage to initial position upon reaching such predetermined point, means for stopping the relieving movements and for holding the grinding wheel out of engagement with the blank when the carriage is being returned to initial position, and means for setting the grinding wheel axis a predetermined distance above the blank axis so that involute helicoids are cut on the side of the blank teeth.

3. In a machine for grinding hobs, the

combination with a rotating blank having teeth in the form of a thread, a conical grinding wheel, and means for effecting feeding and relieving movements by the wheel in timed relation to the blank rotation, of means for moving the blank longitudinally until a predetermined point is reached and then for automatically returning the blank to initial position, means for automatically stopping the relieving movements during the return movement of the blank, and means for varying the position of the wheel axis with respect to the blank axis to effect relieving movements by the wheel in a plane outside the blank axis.

4. In a machine for grinding hobs, the combination with a rotating blank having teeth in the form of a thread, a straight conical grinding wheel, and means for effecting feeding and relieving movements by the wheel in timed relation to the blank rotation, of means for moving the blank longitudinally in timed relation to the rotation thereof and for automatically returning the blank to initial position when the wheel reaches the end of the hob thread, means for automatically stopping the relieving movements and for withdrawing the wheel from engagement with the blank during the return movement, and means for so positioning the wheel with respect to the blank that the blank axis is not included in the plane of the wheel relieving movements.

5. In a machine for grinding hobs, the combination with a rotating blank having teeth in the form of a thread, a straight conical grinding wheel, and means for effecting relative feeding and relieving movements between the wheel and the blank in timed relation to the blank rotation, of means for effecting relative movement between the wheel and the blank parallel to the blank axis and in timed relation to the blank rotation, said last named means also serving to return the blank and wheel to the initial relative position when the wheel is at the end of the blank thread, means for stopping the relieving movements and for separating the wheel and blank during said return movement, and means for so positioning the wheel and blank as to cut involute helicoids on the sides of the blank teeth.

6. In a machine tool, the combination with a blank carrying carriage, a cutting tool, a relieving slide for carrying the tool, a rotating cam member for operating the relieving slide, and adjustable means for connecting the cam member to the slide, of means automatically operated in a predetermined position of said carriage for operating said adjusting means to separate the cam member from the slide and stop the relieving movements.

7. In a machine tool, the combination with

a blank carrying carriage, a cutting tool, a relieving slide for carrying the tool, a rotating cam member for operating the slide, adjustable means for connecting the cam member to the slide, and resilient means for exerting a force to hold the slide away from the carriage, of means automatically operated in a predetermined position of the carriage for moving said adjusting means to separate the cam member from the slide and to withdraw the tool from engagement with the blank.

8. In a machine for grinding hobs, the combination with a blank carrying carriage, a grinding wheel, a relieving slide for carrying the grinding wheel, a relieving cam, an adjusting slide mounted on the relieving slide and having a lug for engaging the relieving cam, and means for normally holding the lug on the adjusting slide and the cam in engagement with each other, of means for rotating the cam to effect relieving movements by the wheel, and means for automatically withdrawing the lug on the adjusting slide from engagement with the cam in a predetermined position of the carriage.

9. In a machine for grinding hobs, the combination with a blank carrying carriage, a grinding wheel, a slide for carrying the grinding wheel, and means for exerting a force tending to move the slide away from the blank, of a relieving cam for effecting relieving movements by the slide, an adjusting slide having a lug thereon for connecting the relieving cam to the relieving slide, means for moving the carriage in timed relation to the blank rotation, means for automatically returning the carriage to initial position when the wheel is at the end of the blank, and automatic means for so moving the adjusting slide during the return of the carriage as to separate the relieving cam from the relieving slide and permit the withdrawing of the wheel from engagement with the blank.

10. In a machine for grinding hobs, the combination with a blank carrying carriage, a grinding wheel, a slide for carrying the grinding wheel, and resilient means for exerting a force tending to move the slide away from the blank, of a relieving cam for effecting relieving movements by the slide, means for moving the carriage in timed relation to the blank rotation, means for automatically returning the carriage to initial position when the wheel is at the end of the blank, and automatic means for separating the relieving cam from the slide during the return movement of the carriage.

11. In a machine for grinding hobs, the combination with a blank carrying carriage, a conical grinding wheel, a slide for carrying the grinding wheel, a spring operated lever for exerting a force tending to move

the slide away from the blank, and a relieving cam for operating the slide to effect relieving movements, of means comprising gearing for rotating the blank, for rotating the relieving cam, for effecting feeding movements by the slide, and for effecting movements of the carriage, and means comprising a cam drum for controlling the direction of movement of the carriage, the starting and stopping of the relieving movement and the position of the wheel with respect to the blank.

12. In a machine for grinding hobs, the combination with a carriage, and a slide movable transversely with respect to the carriage, of means for effecting relieving movements by the slide, automatic means for reciprocating the carriage with respect to the slide, and automatic means for starting the relieving movements when the carriage is moved in one direction and for stopping the relieving movements when the carriage is moved in an opposite direction.

13. In a machine tool, the combination with a carriage, a slide movable transversely with respect to the carriage, and means for effecting relieving movements by the slide, of automatic means for reciprocating the carriage with respect to the slide, and automatic means for moving the slide toward the blank and for starting relieving movements when the carriage is moved in one direction and for stopping the relieving movements and for moving the slide away from the carriage when the carriage is moved in an opposite direction.

14. In a machine tool, the combination with a carriage, a slide movable transversely with respect to the carriage, and means for effecting relieving movements by the slide, of automatic means for reciprocating the carriage with respect to the slide, automatic means for feeding the slide toward the carriage in accordance with the movement of the carriage, and automatic means for starting the relieving movements when the carriage is moved in one direction and for stopping the relieving movements when the carriage is moved in an opposite direction.

15. In a machine tool, the combination with a carriage for supporting a rotating blank, and a slide for supporting a rotating cutting tool, of means for effecting relieving movements by the slide with respect to the blank, automatic means for moving the blank with respect to the tool and for returning the carriage to initial position when the blank and tool occupy predetermined relative positions, automatic means for stopping the relieving movements and for separating the tool from the blank when the carriage is moving in one direction, and for starting the relieving movements and moving the tool into engagement with the

blank when the carriage is moved in an opposite direction.

16. In a grinding machine, the combination comprising a carriage mounted on the main frame of the machine, a feed nut mounted on the main frame, a feed screw mounted on said carriage and co-acting with said nut to move the carriage, means on the carriage for supporting a blank, means on

the frame for locking said nut against movement, means on the frame for rotating the nut to move the carriage at will, and a continuous set of gearing operated from the main frame for rotating the blank and for operating said feed screw. 15

In testimony whereof, I hereto affix my signature.

CARROLL KNOWLES.
